UNITED STATES PATENT OFFICE.

CARL W. VOLLMANN, OF MONTREAL, QUEBEC, CANADA.

REFRIGERATOR.

Application filed June 30, 1926. Serial No. 119,516.

My invention has particular reference to refrigerators for automatic use such as is met in private dwellings, apartment houses, hotels and other places where individuals or families require perishables to be preserved and special foods or water to be frozen for particular purposes. Heretofore no provision has been made of a relatively large freezing chamber contained within a freezing member which in addition will reduce the temperature in the refrigerator for the purpose of chilling the atmosphere therein for preservation purposes and where a uniform temperature will be constantly maintained. It has been attempted to meet this requirement by employing brine containers which owing to the large amount of brine necessary seriously reduces the capacity of the refrigerating chamber and at the same time restricts the freezing chamber to such an extent that it affords small room for use in the freezing of puddings, blocks of ice and the like. It has also been proposed to obtain the result by the use of relatively large freezing liquid containers in the form of coils or sections.

The object of my invention is to meet this requirement and to this end the invention consists of a container having a hollow wall completely encircling the same and presenting a narrow space between its double walls. This produces a closed space through which the freezing liquid circulates, means being provided to introduce a freezing liquid into the bottom of this narrow space and an outlet being provided at the top through which the gas resulting from the expansion of the freezing liquid is returned to the compressor. This construction provides a relatively large cupboard within the freezing member, the inner wall of which is provided with series of rests of different levels for shelves upon which dishes containing the several substances to be frozen may be placed. This enclosing space is preferably composed of elliptic pipe-lengths of different diameters, one set within the other and the space between them is closed at both ends while the chamber enclosed is closed at the back end by a permanent wall while the front end has a cover which is normally closed and adapted to be opened at will.

For full comprehension, however, of my invention reference must be had to the accompanying drawings in which similar reference characters indicate the same parts and wherein:

Figure 1 is a perspective view of a refrigerator for domestic use equipped with my invention;

Figure 2 is a detail longitudinal vertical section of my improved freezing and chilling element;

Figure 3 is a transverse sectional view taken on line 3-3 Figure 2; and

Figure 4 illustrates in detail the means for temporarily holding open the door of the freezing chamber.

The narrow enclosing space of my element preferably consists of a pair of elliptic cast iron pipes *b* and *c* respectively set one within the other as indicated in Figure 3. It will be noted that the enclosing space *d* between these elliptic members is relatively narrow and the chamber *e* within the element is proportionately of large capacity. It will also be seen by reference to this figure that the space is continuous and surrounds the element without interruption, thus permitting a free circulation of the freezing fluid. Fluid is admitted to this circulating chamber by a pipe *g* leading from a small float valve controller *h* which is fed by a pipe *i* from the condenser, not shown. The gas produced by the expansion of the freezing liquid is discharged from the element through pipe *j* to return to the compressor. One end of the element is closed by an annular cap *k* with its center closed by an integral web *k*¹. This cap is secured in place by welding or otherwise fitted over the open end of the enclosing chamber *d* and is thus sealed in place. The opposite end of the element, which is the front, when in place in the refrigerator, is closed by a door *f*. This front end of the element is slightly inclined forwardly from the top to the bottom to provide a sloping face on which the door rests, the door having a hinged knuckle *m* which is hinged between a pair of fixed hinge knuckles *n* cast or otherwise rigidly attached to the outer surface of the element. The door has a handle *o*. The inner member *b* of the element has a series of pairs of ledges *p*, *q* and *r* respectively to support a series of sliding shelves *s*, *t* and *u* respectively. The element is supported on a pair of feet *v* having lugs *w* through straddling a base projection *x* cast on the bottom of the element. This base and these lugs serve to prevent lateral displacement of the element.

When the element is in use in a refrigerator, as shown in Figure 1, it practically fills

the interior of what is usually the ice compartment, sufficient space *z* being allowed for a free circulation of the air within the refrigerator. The enclosed chamber *e* is relatively large and commodious and is capable of receiving a variety of dishes containing food to be frozen, puddings for dessert, for instance, ice cream blocks for preservation, or water to be frozen for domestic use, while 10 the enclosing space *d*, containing as it does, a liquid freezing mixture and being connected directly to the supply of freezing liquid and also being adapted for free circulation of the liquid, need be of only relatively small dimensions.

A refrigerator equipped with my freezing element provides a freezing chamber of maximum dimensions and at the same time maintains a uniform temperature in the 20 freezing chamber and also in the refrigerator for chilling purposes. My improved freezing member is particularly adapted for restoring a chilled atmosphere to a refrigerator after it has been left open for some 25 time, for washing out for instance, or when the refrigerator has been out of use for some time and the element cut off. The door *f* of the element may then be opened slightly as indicated in Figure 3 and the refrigerator 30 door closed. When the element is operated under these circumstances the atmosphere of the refrigerator will be put into rapid circulation and the interior of the freezing chamber, being open will be active in promptly 35 reducing the temperature to any point desired.

A latch 10 pivoted near the front of the top of the interior is adapted to be turned to a position to temporarily hold the door 40 slightly open as shown in Figure 3 when it is desired to promptly lower the temperature of the atmosphere in the refrigerator.

What I claim is as follows:

1. In a refrigerator having an ice compartment and a refrigerating compartment in communication therewith, a door for the refrigerator, a freezing element located within the ice compartment and substantially filling the same and spaced from the wall of 45 the compartment for circulation of the atmosphere of the refrigerator, the element enclosing a relatively large freezing cham-

ber, such freezing element containing a comparatively narrow space within its encircling wall, means for supplying a freezing liquid to the relatively narrow space, means for discharging the gas from the said narrow space, means for closing one end of the freezing chamber and a door for closing the opposite end of the chamber, means for holding the door normally closed and adjustable means for holding the door open, and a pair of supporting feet for the element.

2. A refrigerator for domestic use such as claimed in claim 1, the door of the freezing element of which has a hinged knuckle at its top for engagement in hinged relation with a pair of hinge knuckles formed integrally with the top of the element, and the open side of such element presenting an inclined face for the door to rest upon.

3. A refrigerator for domestic use such as claimed in claim 1, the door of the freezing element of which has a hinged knuckle at its top for engagement in hinged relation 75 with a pair of hinge knuckles formed integrally with the top of the element, and the open side of such element presenting an inclined face for the door to rest upon, and a latch pivoted near the front of the top of the interior of the element for the purpose of temporarily holding the door open.

4. A domestic refrigerator having a compartment for a freezing element and a plurality of compartments for substances to be preserved by the chilling influence from the freezing compartment, a freezing element in the freezing compartment and consisting of nested concentric cast iron pipes of elliptic cross-section, means closing the opposite ends of the space between the pipes, a fixed closure for one end of the element, a door controlling the opposite end of the element, means supporting the element on the floor of the freezing compartment, a freezing liquid supplied to the bottom of the space between the pipes, an outlet for the gas from the top of the said space, and a controller for regulating the level of freezing liquid in the said space.

In testimony whereof I have signed my name to this specification.

CARL W. VOLLMANN.
